UNITED STATES PATENT OFFICE.

JEROME R. GEORGE, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL HOUSING.

Application filed December 4, 1922. Serial No. 604,970.

To all whom it may concern:

Be it known that I, JEROME R. GEORGE, a citizen of the United States, residing at Worcester, in the county of Worcester and 5 Commonwealth of Massachusetts, have invented a new and useful Improvement in a Rolling-Mill Housing, of which the following, together with the accompanying drawings, is a specification.

10 The present invention relates to rolling mills, with particular reference to an improved construction of the housings which provide support for the necks or gudgeons of the cooperating rolls. The invention re- 15 sides in the features of construction hereinafter more fully set forth, reference being had in this connection to the accompanying drawings, wherein—

Fig. 1 is a side view of a roll housing 20 having my invention applied thereto.

Fig. 2 is a transverse sectional view of the parts shown in Fig. 1.

Fig. 3 is a side view of a modified construction.

25 Fig. 4 is a transverse sectional view of the parts shown in Fig. 3.

Like reference characters refer to like parts in the different figures.

Referring first to Figs. 1 and 2, the invention is shown applied to a roll housing which consists, as usual, of opposite upright sides 1, 1, rising from a suitable base 2 and supporting between them, transversely, a lower roll 3 and an upper roll 4. The necks 30 or gudgeons 5, 5 of lower roll 3 rest on suitable bottom bearings 6, 6, each disposed and secured in the lower end of a vertical recess or opening provided by housing side 1. In a like manner, the necks or gudgeons 7, 7 of upper roll 4 find support in lower bearing blocks 8, 8, the latter being seated on ledges or shoulders 9, 9 provided by the housing sides.

On account of the relatively large diameters of the roll necks or gudgeons 5 and 7, and more particularly in view of the necessity, from time to time, for turning down the roll diameters, thus bringing their axes even closer together, it is impracticable, in 50 the space available between the upper and lower roll necks, to accommodate two ordinary bearing blocks in superposed relation, one to support the gudgeon of the upper roll and the other to hold down the gudgeon of

the lower roll. Notwithstanding this, it is 55 necessary for the proper operation of the rolls and for the range of adjustment demanded for the mill, to provide means independent of the fixed lower bearings 8 of the upper roll for holding down the lower 60 roll and for opposing the vertical adjustment of the latter by the usual screw operating adjusting wedges 10, 10.

The present invention meets this requirement by the special construction of the bearing blocks 8, 8, which support the upper roll and the bearing blocks 11, 11, which oppose upward movement of the lower rolls; as shown in Figs. 1 and 2, each block 8 has a bottom groove or recess 8' running transversely of the roll axis, said groove or recess being of sufficient width and depth to accommodate the adjacent block 11 for the lower roll when the latter is adjusted upwardly. Each block 11 is pressed down 70 against its roll neck by a transverse bar 12, the latter passing through suitable slots 13, 13 in the housing sides, and being subjected at its ends to downward pressure applied through a pair of inverted bolts 14 and 15, 75 which bolts are adjustably held in threaded openings of projecting lugs 16, 16. As shown in Fig. 1, the ends of bar 12 are slightly recessed, to receive the heads of bolts 14 and 15, whereby to prevent endwise 80 movement of said bar 12.

By the construction above described, the lower bearings for the upper roll and the upper or holding down bearings for the lower roll are essentially telescopic, in that 90 movement of the last named bearing is permitted, notwithstanding the limitations of space imposed by the close proximity of the roll necks. Furthermore, the bar 12, employed for holding down the lower roll, is, 95 by reason of its length and relatively small cross section, of sufficient flexibility to permit any ordinary adjustment of the bottom roll without affecting, appreciably, the downward pressure on bottom roll neck. 10 When changing rolls, the bars 12 are drawn out endwise through the slots 13; following this, the removal of the housing cap 17 permits both rolls and all their bearings to be removed from the housing. The bars 12, 10 as here shown, are curved upwardly, in order not to interfere with the guide devices, not shown, that are bolted on each face of the

housing. However, I am not limited to this construction, as said bars 12 may be straight, or if desired, bend downwardly.

Referring to Figs. 3 and 4, the modification therein shown involves lower bearing blocks 18 and 19 respectively, for the lower and upper rolls 3' and 4',—the last named bearing blocks 19 for the upper rolls being of the usual construction and supported on ledges 20, 20 of the housing. As a variation of the interior telescopic arrangement of the holding down device for the lower roll, as shown in Figs. 1 and 2, the present modification contemplates a bearing block 21, which fits over the neck of lower roll 3' near the extreme outer end of said neck, and at a point outside of the housing. The holding down device for this bearing block 21 consists, as before, of a transverse bar, here indicated by the numeral 22, which is acted upon by inverted bolts 23, 23, corresponding to the bolts 14 and 15 of Fig. 1. In this arrangement, the accommodation of a bottom bearing for the upper roll and a top bearing for the lower roll is effected by offsetting said bearings in the space between the roll necks, with one bearing in the housing and the other substantially outside.

I claim,

- 30 1. In a rolling mill housing, upper and lower bearing members for the necks, respectively, of lower and upper rolls, said bearing members being telescopically arranged between said necks to permit upward movement of said upper bearing member when said lower roll is raised.
- 40 2. In a rolling mill housing, an upper bearing member for the neck of a lower roll and a superposed lower bearing member for the neck of an upper roll, said bearing members being independently supported in overlapping relation between said roll necks to permit of relative movement between them when the lower roll is adjusted.
- 45 3. In a rolling mill housing, a pair of independent opposed bearing members in the space between the roll necks, one for supporting the upper roll and the other for holding down the lower roll, means for raising said lower roll, and said bearing members being telescopically arranged, whereby to accommodate both in said space when said lower roll is raised.
- 50 4. In a rolling mill housing, a fixed bearing for supporting the upper roll, said bearing being disposed in the space between the

roll necks, in combination with an upper bearing for holding down the lower roll, means for raising said lower roll, and said upper bearing being in telescopic relation to said first named bearing within the space between said roll necks to permit the raising of said lower roll.

5. In a rolling mill housing, a fixed bearing for supporting the upper roll, said bearing being disposed in the space between the roll necks, in combination with an upper bearing for holding down the lower roll, said upper bearing being offset from said first named bearing within the space between said roll necks.

6. In a rolling mill housing, a holding down device for the lower roll, comprising a member bearing centrally on the upper bearing for the neck of said roll and exerting pressure thereon through the action of adjustable devices at each end, exteriorly of the housing, said member being free to move in a slot provided by the lower bearing for the upper roll neck.

7. In a rolling mill housing, a holding down device for the lower roll, said device comprising a flexible bar bearing at its center on the upper bearing for the neck of said roll.

8. In a rolling mill housing, a holding down device for the lower roll, comprising a member bearing centrally on the upper bearing for the neck of said roll, and adjustable means, comprising inverted bolts carried by said housing, for exerting pressure on the ends of said member.

9. In a rolling mill housing, a holding down device for the lower roll, comprising a member bearing centrally on the upper bearing for the neck of said roll, and adjustable means, comprising inverted bolts carried by said housing, for exerting pressure on the ends of said member, one of said bolts being interlocked with said member to prevent displacement thereof.

10. In a rolling mill housing, a holding down device for the lower roll, comprising a member bearing centrally on the upper bearing for the neck of said roll in combination with inverted bolts threaded in holes in said housing for exerting pressure on the ends of said member, said holes being closed at the top, to exclude scale and dirt from the threads.

Dated this 9th day of November, 1922.
JEROME R. GEORGE.
